UNITED STATES PATENT OFFICE.

ALFRED H. BENJAMIN, OF EAST ORANGE, NEW JERSEY, ASSIGNOR TO THE FIRM OF BENJAMIN AND JOHNES, OF NEWARK, NEW JERSEY.

MEANS FOR CONNECTING UNDERGARMENTS.

No. 798,943.

Specification of Letters Patent.

Patented Sept. 5, 1905.

Application filed October 31, 1904. Serial No. 230,694.

To all whom it may concern:

Be it known that I, ALFRED HANSON BENJAMIN, a citizen of the United States, residing at East Orange, in the county of Essex and State of New Jersey, have invented an Improvement in Means for Connecting Undergarments, of which the following is a specification.

My invention relates to a means of connecting a corset-cover, underwaist, chemise, or other undergarments or hose-supporters to a corset at the fastening devices of the front steels for both insuring the location centrally of the said undergarment upon the figure, but also for holding the same down and preventing a riding-up tendency, so as to insure the better fit of outer garments and fix the relation of the outer and the undergarments to one another, contributing to perfection of their combined ornamental appearance under certain conditions of dress.

My invention comprises one or more lengths of tape secured to the inner or under surface of an undergarment, such as a corset-cover, underwaist, or chemise, so as to form a loop, eye, or opening at a point in close proximity to the lower of the fastening devices of the front steels of the corset, the connection between the said parts being made by the eye member of said fastening passing through the loop or opening prior to connecting to said eye member the complementary stud member of the other steel, thus connecting the undergarment and corset.

The preferred form of my invention consists of a strip or flap of fabric of suitable form to be secured to the undergarment by sewing and to one side of which one or more lengths of tape are secured, the said strip or flap being secured to the undergarment by any one handy with the needle. These loops or openings are preferably made by taking a predetermined length of tape and securing the ends either to the undergarment itself or to the strip or flap of fabric and then crossing the same at equal distances by short lengths of tape sewed down throughout their length to the undergarment or to the strip or flap and at right angles to the predetermined length of tape, which consequently both divide up the tape into loops and secure the same at points intermediate to the sewed ends.

In the drawings, Figure 1 is an elevation showing a portion of the fabric of an under-

garment and tapes sewed thereto so as to 55 form the loops of my invention, and Fig. 2 is a vertical section of the same. Fig. 3 is an elevation from the other side of the part shown in Fig. 1, together with an elevation at the lower front portion of the corset, showing the 60 connection between the fastening devices of the corset and the devices of my invention. Fig. 4 is a cross-section of the parts shown in Fig. 3 at the line *x-x*. Fig. 5 is an elevation, and Fig. 6 a section, of the preferred form of 65 my invention. Fig. 7 is an elevation, and Fig. 8 a section, of a modification of the preferred form. Fig. 9 is an elevation of a corset-cover or underwaist and the lower portion of a corset around which the same extends, illustrating the application thereto of the devices of my invention. Fig. 10 is an elevation from the back of a flap adapted to be connected to a corset-cover or underwaist, showing the features of my invention. Fig. 75 11 is a similar view to Fig. 10, showing a modified form of the invention; and Fig. 12 is a view from the back of the fabric section of hose-supporters with the device of my invention applied thereto. The sections Figs. 2, 80 6, and 8 are without section-lines for greater clearness.

Referring to Figs. 1, 2, 3, and 4, *a* represents a part of the fabric of an undergarment, such as a corset-cover, underwaist, or chemise; *b*, a short length or strip of tape connected thereto by lines of sewing *2* at the respective ends, and *c* represents lengths of tape placed transversely of the longer piece *b*, crossing the same and secured to the fabric by lines of 90 sewing *3*, and so dividing the length of tape *b* into two or more loops. *d* represents part of body of a corset, *e* the corset-steels at the front, and *f, f'* the fastening devices upon the respective steels and by which they are 95 held together. Figs. 3 and 4 show the two lower corset-steel fastening devices *f, f'* as connected to the loops of the tape *b*, the eye members of such fasteners passing through the loop or loops provided to connect the 100 said eye member and complementary stud member, and the act of hooking up the corset and at the same time connecting the undergarment to the corset.

Referring to Figs. 5 to 8, *g* and *h* represent 105 fabric sections preferably of two thicknesses of fabric connected by lines of sewing *4* at the respective ends. In Figs. 5 and 6 the

- long tape-strip *b* passes centrally and longitudinally of the fabric section *g* and is intersected with the transverse and shorter pieces of tape *c*, sewed to the fabric section *g* and to the tape *b*, dividing the tape *b* into three loops. In Figs. 7 and 8 loops *b'*, made by doubling pieces of tape, are formed, the free ends being connected to and beneath the transverse tapes *c* by the lines of sewing that connect said transverse tapes to the fabric section *h*. The fabric sections *g* *h* in these figures, as articles of manufacture to be sold in the open market, are adapted to be connected, by any one handy with a needle, to the under surface of an undergarment—such as a corset-cover, underwaist, or chemise—or even to the under surface of the fabric section of hose-supporters *l*, Fig. 12, by lines of sewing extending around the respective edges.
- In Fig. 9 I have illustrated part of a corset-cover or underwaist *i* and part of a corset *d'* over which the same extends and have shown in connection therewith a flap *k*, which specifically forms the subject of an application for Letters Patent filed by me October 31, 1904, Serial No. 230,695, the same, with Figs. 10 and 11, showing the flap in larger size, being herein illustrated and described for the generic structure. This flap *k*, referring to Fig. 10, is provided on the under side with the long tape *b* and the short transverse crossing tapes *c*, connected to the flap, the same as hereinbefore described with reference to Figs. 1 and 5, and adapted for connection with the fastening devices of the corset-steels, as hereinbefore described with reference to the same figures.
- The flap, Fig. 11, is provided with loops similar to the fabric section *h*, Fig. 7, and is to be connected to the corset-steel fastening devices in a similar manner—that is, by passing one or more of the eye members of the said fastening through one or both of the loops prior to connecting the eye member of the fastening to its complementary stud member on the other steel.
- In Fig. 12, *l* represents the fabric section of a hose-supporter of well-known character, to the back or under surface of which are secured the devices of my invention—that is, the long tape *b* and the shorter transverse tapes *c* connected by lines of sewing, so as to form several loops in the tape *b*, said loops being adapted for connection to the fastening devices of the corset-steels, as hereinbefore described.
- From the foregoing it will be apparent that, regardless of the character of the undergarment or of the employment of my invention with a hose-supporter, the function performed is the same—that is, the undergarment is held down and a riding-up tendency is prevented. The undergarment is also held centrally and a turning-around movement or displacement prevented. This is true with an application

of the invention to the hose-supporter, because therein, while the strap that passes around the corset holds the supporter from being drawn downward, the loop devices of my invention prevent the same from being moved from side to side over the front of the corset either when the person sits down or by the pulling action of the supporter-straps in walking.

I claim as my invention—

1. The combination with an undergarment, of a strip of tape sewed thereto at its ends upon the under surface thereof and adapted to have the fastening devices of the steels of a corset passed through the same for connection therewith.

2. The combination with an undergarment, of a strip of tape sewed thereto at its respective ends upon the under surface thereof, and at least one short length of crossing tape sewed thereto and to the undergarment forming of the strip of tape loops upon the under surface of the undergarment adapted for connection with the fastening devices of the steels of the corset.

3. A fabric section adapted to be sewed to the under surface of an undergarment, a strip *b* of tape connected thereto at its respective ends, one or more short transverse strips of tapes *c* crossing the same sewed thereto and to the fabric section forming in the strip *b* two or more loops adapted for connection with the fastening devices of the steels of the corset.

4. The combination with an undergarment, of a strip of tape sewed to the under surface thereof at its respective ends, two short lengths of tape also sewed to the under surface of the undergarment and crossing the first length of tape at spaced-apart intervals and forming of the strip three loops upon the under surface of the undergarment adapted for connection with two of the fastening devices of the steels of a corset.

5. A fabric section adapted to be sewed to the under surface of an undergarment, a tape sewed to one surface of said fabric section at its respective ends and at least one short length of tape crossing the same and sewed to the section and to the first-named tape forming in the strip of tape at least two loops adapted for connection with the fastening devices of the steels of a corset.

6. The combination with an undergarment, of a strip of tape sewed thereto at its ends and at, at least one intermediate place and upon the under surface thereof to form openings adapted for connection with the fastening devices of the steels of a corset.

Signed by me this 28th day of October, 1904.

ALFRED H. BENJAMIN.
